UNITED STATES PATENT OFFICE

2,415,297

PUSH-BUTTON SWITCH

William C. Linton, Washington, D. C., assignor
to Fuse Indicator Corporation, Rockville, Md.,
a corporation of Delaware

Application October 10, 1944, Serial No. 558,056

5 Claims. (Cl. 200—159)

1

The present invention relates to electrical switches and more particularly to wall switches for use in ordinary lighting systems of rooms and buildings, having amongst its principal desiderata the provision of a wall switch which will visibly designate the open position of the circuit closer whereby one may more readily find the switch when located in dark or secluded places.

Another equally important desideratum of the invention is to provide a switch in which the external appearance thereof will be more ornamental and pleasing to the observer than that of ordinary wall switches, in that the cover plate thereof may be of various colors or combination of colors; the unsightly fastening elements for the cover plate are hidden from view and a single push-button is employed which, due to its design and color will, when used in combination with the cover plate, blend with its color and harmonize therewith.

A still further object of the present invention is to provide a circuit closer for controlling the flow of current in electrical lighting systems which is of a compact design, improved construction and arrangement whereby it may be placed within the conventional cutout box and connected to the wiring extending therein, and for a consideration of what I believe to be novel and my invention, attention is directed to the accompanying description and the claims appended thereto.

In the accompanying drawings:

Fig. 1 is a plan view of the switch and its cover plate embodying the present invention.

Fig. 2 is a vertical longitudinal section through the cover plate illustrating the switch casing and push-button thereof in side elevation and the switch being supported within a cutout box, which latter is illustrated in dotted lines.

Fig. 3 is a transverse section through the cover plate showing the switch casing in end elevation.

Fig. 4 is a vertical transverse section through the switch when employing a liquid contact circuit closer and the cover plate thereof.

Fig. 5 is a plan view of the supporting bar and switch with the cover plate, lamp and lens of the push-button removed.

Fig. 6 is a vertical longitudinal section through the switch casing and cover plate therefor showing the normal position of the push-button.

Fig. 7 is a similar view showing the position of the push-button when being fully actuated or moved inwardly for transmitting movement of the circuit closer.

2.

Fig. 8 is a detail section on the line 8—8 of Fig. 6 showing the circuit closer in elevation.

Fig. 9 is a detail side elevation of the bracket for the circuit closer.

5 Fig. 10 is a vertical longitudinal section through the switch when employing a snap circuit closer.

Fig. 11 is a horizontal section taken on the line 11—11 of Fig. 10 in the direction of the arrow points, and

10 Fig. 12 is a vertical transverse section of the same.

Referring now more particularly to the accompanying drawings, the wall switch embodying the present invention comprises a cover plate 1 having a circular opening 2 formed therein and projecting within this opening are a pair of apertured lugs 3 through which extend the attaching screws 4. This cover plate is preferably of the conventional rectangular configuration so as to fit

15 closely adjacent the wall and completely cover the switch and cutout box 5 installed therein. The cover plate is preferably molded from a plastic material. The material used may be opaque and of various colors or combination of colors or it 20 may be transparent with a colored background which is visible from the exterior face of the cover plate.

The attaching screws 4 of the cover plate extend within threaded openings formed within the 25 ears or projections 6, which latter form a part of the supporting bar 7. The opposite ends of this supporting bar 7 may be connected in the usual manner to the cutout box 5 by means of the screws 8 in order that the switch and its cover

30 plate may be attached thereto and supported thereupon. This supporting bar has an enlarged medial portion 9 in which is formed a circular opening 10 of a diameter equal to that of the opening 2 formed within the cover plate, whereby 35 the projections 6 will register with the projections 3 of the cover plate. The extremities 11 of the medial portion 9 of this bar are bent downwardly so as to extend over the opposite side faces of the switch housing or casing 12.

40 The casing 12 has formed with its opposite ends apertured projections 13 through which extend the screws 14, which latter engage the threaded openings 15 of the supporting bar 7, whereby the casing 12 may be attached to the supporting bar 45 and suspended therefrom within the cutout box 5. This casing 12 has a compartment formed therein, the upper end of which is opened and the medial enlarged portion 9 of the bar 7 extends completely across the opened upper end of the 50 casing. Communicating with the lower end of

the compartment formed within the casing is a well formed by means of the bulged portion 16 and the bottom of the casing extends as at 17 and 17' from the opposite ends of the wall to form stops for a purpose which will be later described. Also formed with the opposite ends of the casing are the lugs or projections 18 and upon each of which is seated the outer end of a contact member 19. Each contact member is provided with a terminal screw 20 for clamping thereto the usual conductors of the wiring system extending within the cutout box 5. These contacts 19 extend through openings in the end walls of the casing 12 and their lower edges rest upon the ledges 21 formed with the casing and extending along each side of the well formed in the bottom thereof.

The inner extremities of each contact 19 are provided with spherical projections which fit into complementary depressions 22 in each of the terminals of the liquid contact circuit closer 23.

This liquid contact circuit closer or button 23 is of a conventional design and better illustrated and described in Patent No. 2,101,092, issued December 7, 1937. This circuit closing button is supported within the casing by means of the contact terminals 19 in order that its lower portion may oscillate within the well formed within the bottom of the casing. This mercury circuit closing button, when in the position as shown in Fig. 6 of the drawings, interrupts the electrical circuit in which the terminals 19 are included but when moved to the position as shown in Fig. 7 of the drawings, the circuit is closed whereby the current may flow therethrough.

In order to actuate this circuit closer to its open or closed position, a connection is employed between the push-button 24 and circuit closer whereby when the push-button is depressed or pushed inwardly within its cover plate, the button 23 may be oscillated in opposite directions. Secured to this circuit closing button 23 is a sectional bracket 25, as best shown in Figs. 8 and 9 of the drawings. Each section of this bracket has an enlarged central portion 26 which fits over the terminals of the circuit closer 23 and has a knob projecting therefrom which is seated within a corresponding recess 27 formed within the terminals, whereby when the bracket is oscillated, the button 23 will be caused to move therewith. The upper and lower ends of the sections of this bracket are connected together by means of the pins 28 and extending diametrically opposite from each section of the bracket are the arms 29.

The push-button comprises a plunger 30 which is of a cylindrical design capable of passing through the opening 10 of the supporting bar 7 and opening 2 of the cover plate as it is provided with the vertically extending grooves 72 which accommodate the lugs 3 and the projections 6 of the cover plate and supporting bar respectively. Extending with the lower end of the plunger is an annular flange 31 which, when the plunger is inserted through the openings from the lower faces of the supporting bar and cover plate, and abut against the lower face of the enlarged portion 9 of the supporting bar to limit the outward movement of the push-button. Formed within the lower end of the this plunger 30 is a recess 32 and extending therethrough is a pivot pin 33. Pivotally connected to this pin 33 is an inverted U-shaped actuator 34 and each arm of this actuator is provided with a shoulder or projection 35, which latter are adapted to engage the outer ends of the arms 29 of the bracket connected to

the button circuit closer. Connected to the uppermost pin 28 of this bracket is a coil spring 36 and the opposite or upper end of this coil spring is seated within a recess formed by means of a knob 38 projection extending from the lower face of the actuator 34 below its pivot connection. This spring normally tends to elevate the actuator 34 and the push-button 24 in the position as better shown in Fig. 6 of the drawings and when in this latter position, pressure is also exerted upon the circuit closer 23, whereby it will be caused to assume the position as shown and stopped when an arm 29 contacts with a shoulder 17 formed with the casing 12.

The circuit closer, when in the position as shown in Fig. 6 of the drawings, is such as to cause the electrical circuit connected thereto to be opened but when it is desired to close the electric circuit by means of this circuit breaker, the operator will, by applying pressure to the push-button 24, force the same inwardly until it assumes the position as is illustrated in Fig. 7 of the drawings. As the push-button 24 is being forced inwardly, the right hand shoulders 35 of the actuator will first engage the uppermost end 29 of the bracket which is attached to the circuit closer 23, and force this arm 29 downwardly until it abuts against the stop 17 whereby the circuit closer 23 will be rotated in a clockwise direction and the electrical circuit to which it is included closed. At the same time, the coil spring 36 is compressed and its lower end moves with the bracket 25 until it assumes the position as is shown in Fig. 7 of the drawings. As pressure is released from the push-button 24, it will be moved outwardly by means of the coil spring 36 until the flange 31 abuts against the lower face of the enlarged portion 9 of the crossbar. This compressed coil spring 36 will also retain the bracket 25 in the position as shown in Fig. 7 as the pivot point 28 is positioned off-centre from a line extending through the pivot points 33 and 22. However, the actuator 34 which is attached to the push button will also again be elevated at the position as shown in Fig. 6 whereat the left hand shoulder 35 thereof will be positioned immediately above the elevated arm 29 of the bracket 25 as is shown in Fig. 7. The actuator will now be in a position whereupon with again applying pressure to the push-button 24, the circuit breaker 23 will be moved in an anti-clockwise direction until it again assumes the position as shown in Fig. 6 of the drawings, and the circuit opened. From this arrangement, it is obvious that an oscillating movement may be transmitted to the circuit breaker for opening and closing the electric circuit to which it is included and this oscillating movement is transmitted direct by a single reciprocating push-button.

Whereas, in the foregoing I have described a liquid circuit closer 23, any other type of circuit maker or breaker may be employed or that type as is shown in Figs. 10 to 12 of the drawings, in which the casing 40 is attached to and suspended from the bar 7 by means of the attaching screws 41, which latter extend through the apertured bosses 42 formed with the casing.

Seated within the casing are a pair of conductor plates 43 each having at its outer end a flange into which is threaded a terminal screw 44 for clamping a wire conductor to each plate. Secured to each plate is a spring contact 45 which is at times engaged by a circuit closer 46, which latter is preferably made of metal and a good conductor of electricity, whereby when the

circuit closer engages the contacts 45, the electrical circuit in which they are included will be closed, but when the circuit closer is out of engagement with the spring contacts 45, the electrical circuit will be opened. Formed with and 5 projecting from the bottom of the casing 40 are a pair of spaced standards 47, each having a recess formed in the upper extremity thereof for rotatably supporting the circuit closing support, which latter consists of a cylindrical bar 59 having its opposite ends positioned within the recesses of the standards and depending from this bar is an arm 51, to the lower end of which the circuit closer 46 is attached. This bar 59 has formed therewith and extending in diametrically opposite directions the arms 52 and 53. The arms 52 and 53, together with the bar 59, form a pair of openings 54 through which extend the lower ends of the actuator 34. Also formed with this bar 59 is a slotted boss 55 through which extends the lower end of an operator blade 56 and the opposite end of this blade 56 is adapted to travel within a recess 57 formed within the actuator 34. A coil spring 58 extends between the enlarged portion of the blade 56 and the boss 55, which spring 58 serves the purpose of holding the push-button in an elevated position in the same manner as the spring 36 shown in the preferred form of the invention. The operator blade 56 serves the purpose of throwing the actuator 34 in an opposite direction to which the bar 59 is oscillated, in order that a shoulder 35 of the actuator will be moved to a position whereat it may be caused to engage the outer extremity of either one of the arms 52 or 53.

When the circuit closer is in the position as shown in Fig. 19 of the drawings, the coil spring 58 will retain the bar 46 out of contact with the spring contacts 45, whereat the electrical circuit will be opened and remain opened.

When it is desired to close the switch, the operator, by forcing the push-button within the switch casing, will cause one of the shoulders 35 of the actuator to engage the uppermost end 52 of the circuit closer supporting frame, whereby this end 52 will be forced downwardly until it engages the stop 59. The circuit closing bar 46 will also be moved into engagement with the spring contacts 45. At the same time, the coil spring 58 will be compressed and the operator blade 56 will be moved within the slot 57 to a position opposite that shown in Fig. 10 of the drawings. When pressure is relieved from the push-button 24, the coil spring together with the blade 56, will shift the actuator 34 so that the shoulder 35 at the righthand side of the actuator, as shown in Fig. 10, will be in a position to engage the end 53 of the arm of the circuit closer supporting frame. To again open the electrical circuit, pressure must be applied to the push-button 24 whereupon the arm 53 will again be moved downwardly until it contacts with the stop 60. At this time, the circuit closer 46 is moved out of engagement with the spring contacts 45 and the electrical circuit again opened. When the pressure is relieved from the push-button 24, the blade 56 will return to the position as shown in Fig. 10 of the drawings and the actuator 34 shifted until it assumes the position as shown, whereat, one of the shoulders 35 thereof will be in line with the arm 52. From the foregoing, it is obvious that the actuator 34 is shifted from side to side by means of the coil spring and blade 56, whereby one of its shoulders will be moved out of engagement with one of the arms of the circuit

closer supporting frame and the opposite shoulder 35 moved to a position whereat it can be moved into contact with the opposite arm of the circuit closer supporting frame.

Formed within the upper face of the plunger 30 is a recess 61 having arranged therein a neon glow lamp 62, one lead wire 63 which extends down through an opening 64 formed in the plunger 30 and is connected to one of the terminals 19 or 44 of the switch, whereas, the opposite lead wire 65 of the lamp 62 is seated within a recess 66 formed within the plunger 30. Another lead wire 67 is connected to the opposite terminal 19 or 44 of the switch and extends up through an opening 68 formed within the plunger block 30 and is connected to the lead wire 65 of the lamp extending within the recess 66 by means of a leak resistor 66' to be arranged within this recess. The lead wires 63 and 67 each have a coil formed therewith to allow for the movement of the plunger 30. The neon lamp and leak resistor are connected in series with the terminals 19 or 44 of the switch but in parallel thereto, whereby, when the switch is open, the current may be permitted to flow through the lamp for causing the same to glow but when the switch is in closed position, the current will flow through the same and thereby cause the lamp to be extinguished.

In order to cover the lamp and the upper end of the plunger 30, a lens is provided which is preferably molded from a transparent or translucent material having a top portion 69 and a pair of flanges or depending side walls 70 which extend over the upper reduced end of the plunger 30 having a snap engagement with the plunger for locking the lens thereto. The two opposite spaces 71 arranged between the flanges 70 register with grooves 72 arranged within the side walls of the plunger 30, whereby, the openings 40 formed will permit the push-button and lens attached thereto to be forced inwardly when pressure is applied thereto and the boss 3 formed with the cover plate, as well as the bosses 6 formed with the supporting bar 7, may travel therein. 45 From this construction and arrangement of parts, it is obvious that the outer circular face 68 of the lens completely covers the plunger as well as the attaching screws 4, which connect the cover plate to the supporting bar 7, in order that one viewing the cover plate and switch will only see the cover plate and the lens of the push-button, thereby hiding from view the unsightly connecting screws 4 or other fastening means that may be used in connecting the cover plate to its support.

The lens of the push-button in addition to being transparent or translucent in order that the rays of light from the lamp 62 may emit therefrom, can be molded from plastic materials 60 of various colors or colors which would correspond to or harmonize with the cover plate 1, in order that the complete switch, when placed in the wall of a room, may harmonize or blend with the color scheme of furnishings of such room, thereby making an attractive ornament which is not unsightly as is true of the conventional wall switches and cover plates therefor and, in addition, will have a glow of light which will enable one to readily detect the same in a 65 dark room, whereupon, by pressing the push-button 24, the circuit closer will be actuated for closing the electrical circuit and thereby extinguish the lamp 62. When it is desired to turn off the lights included within the electrical circuit, the operator may again press the push- 70 75

button 24 wherein the electrical circuit will be broken and the lamp 62 again caused to glow.

From the foregoing, it is obvious that a single push-button can be used with my type of switch for opening and closing an electrical circuit and in addition thereto, will have means for illuminating the same, as well as having an ornamental and attractive appearance.

Manifestly, the construction herein shown is capable of considerable modification and such modifications as come within the scope of my claims, I consider within the spirit of my invention.

I claim:

1. An electrical wall switch comprising in combination a supporting bar, a receptacle having a switch arranged therein, an enlarged medial section formed with said bar, extending over and connected to said receptacle, a cover plate, said cover plate and enlarged section of said supporting bar having aligning openings therein, aligning lugs formed with and extending within the openings of said cover plate and supporting bar, fastening elements extending through said lugs for attaching said cover plate to said supporting bar, a push button extending through said aligning openings of said cover plate and supporting bar movable into position defining the opened and closed position of switch within said receptacle, said push button having vertically extending grooves therein for receiving said lugs, a lens secured to said push button and said lens at all times extending over said fastening elements.

2. An electric wall switch comprising in combination a supporting bar, a switch mechanism attached thereto, a cover plate extending over said switch mechanism, a push button movable through said cover plate and having one end connected to said switch mechanism, a pair of aligning lugs formed with said supporting bar and cover plate, screws removable from the outer face of said cover plate and extending through said lugs for detachably connecting said cover plate to said supporting bar, means carried by said push button extending over said lugs and screws when the latter connects said cover plate to said supporting bar and means whereby said cover plate may be removed from said supporting bar without removing said push button.

3. An electric switch comprising in combination a supporting bar, an enlarged medial portion formed with said bar and having an opening formed therein, a casing having a switch mechanism mounted therein, means for connecting said casing to said enlarged medial portion of the supporting bar, a removable cover plate extending over said casing and having an opening therein aligning with that of said supporting bar, a push button extending through said openings and having one end connected to said switch mechanism, an indicator for defining the opened and closed positions of said switch mechanism

10

and arranged within said push button, means for detachably connecting said cover plate to said supporting bar, said detachable connecting means being removable from the outer face of said cover plate, a lens extending over said indicator and detachable connecting means when attached to said push button and means whereby when said lens is removed from said push button said detachable connecting means and cover plate may be removed for gaining access to said switch mechanism without disconnecting said push button from the latter.

4. An illuminated wall switch comprising in combination a supporting bar, a casing having a switch mechanism arranged therein connected to said bar, a cover plate detachably connected to said supporting bar and extending over said casing, a push button movable through said cover plate and connected to the switch mechanism arranged within said casing, fastening elements removable from the outer face of said cover plate for detachably connecting the latter to said supporting bar, the opposed walls of said push button having vertically extending grooves formed therein for receiving said fastening elements, said push button having a recess therein, a lamp positioned within said recess and a lens, detachably connected to said push button and extending over said lamp, grooves and recess formed therein.

5. An electrical wall switch comprising in combination a receptacle having a switch mechanism arranged therein, a removable cover plate extending over the switch mechanism within said receptacle, a single switch button movable through said plate and into positions defining the opened and closed positions of said switch mechanism, screws for connecting said cover plate to said receptacle and being removable from the outer face of said plate, covering means extending over said screws without contacting said plate and means for connecting said covering means to said switch button whereby the latter may be moved through said plate without uncovering said screws.
